UNITED STATES PATENT OFFICE.

THOMAS J. COURTNEY, OF ORANGE, NEW JERSEY, ASSIGNOR OF ONE-HALF TO JOHN F. CONNORS, OF SCRANTON, PENNSYLVANIA.

STOKER GRATE.

Application filed March 7, 1924. Serial No. 697,621.

- This invention has for its object to provide an improved stoker grate section by providing means which will cut off the direct flow of air between adjacent sections 5 in the line of travel of said grates; by providing an improved form of opening in the grate section through which the air passes; and providing improved means for securing the grate sections to the grate bars.
- 10 The various features of the invention will appear from the detailed description taken in connection with the accompanying sheet of drawings forming part of this specification, Fig. 1 in the drawings being a bottom 15 perspective view of the grate section, one of the securing elements shown in position ready to be inserted on the holding means on the grate section; and Fig. 2 is a longitudinal section taken through a pair of adjacent 20 grate sections and showing one of said sections secured on the grate bar.
- In the drawings, the grate bar to which the respective grate sections are secured is indicated at 1, it being understood that the 25 grate bars are secured to chains which carry the grate section from one end of the stoker to the other. The grate bar has a shelf 2 having a hole therein for the reception of a bolt 3 which has a flat head 4 adapted to seat 30 a depression in the bottom of a plate 5 which has upwardly and inwardly directed claws 6 for holding a T-head 7 which is secured in any suitable manner as by means of rivets 8 to the body of the grate section. By providing a flat head 4 on the bolt and providing a flat seat in the plate 5, the plate will 35 be held to the grate section without danger of breakage of the plate as often occurs when a tapered head is used on the bolt.
- 40 The use of a flat head 4 on the bolt also overcomes the liability of the head extending above the top surface of the plate as frequently occurs when a tapered bolt head is used.
- 45 The grate section is provided with a plurality of holes for the passage of air upwardly and said holes flare outwardly as at 11 from a point below the surface of the grate and flare outwardly as at 12 downwardly from said point. By having the 50 holes flare outwardly toward the top of the grate, there is less likelihood of the holes becoming burned and closing up when the fire is allowed to burn to the grate surface.
- 55 Furthermore when air leaves the mouth of
- the air passages through said flares it has a spreading effect through the fuel which means good combustion. I consider this an important feature of the invention because so far as I am aware grates have hitherto 60 been constructed with holes of a uniform diameter for some distance into the body of the grate section.
- Another important feature of the invention is the provision of a downwardly and 65 forwardly extending extension 13 having a downwardly extending flange 14 which extends transversely of the said extension, said flange resting on the grate bar 1 and preventing the flow of air beneath said extension. Disposed above said extension 13 is an 70 adjacent grate section 9 as clearly shown in Fig. 2. The extension 13 is provided with a plurality of lugs 15 on which the adjacent 75 end of the grate section 9 rests, said lugs serving to hold the adjacent grate section in the same plane as the other grate section. It will be noted that the extension 13 is 80 spaced from the adjacent grate section 9 thus permitting air to reach the holes in the extreme end of the grate section. It will also now be understood that the transversely extending flange 14 prevents a free 85 flow of air between the adjacent grate sections, the result being that the air must come or pass directly from beneath the section. It is therefore apparent that there is less tendency for the air current to sweep directly below the grate section without passing upwardly through the holes. In other 90 words, by arranging a flange 14 between the ends of the grate section the air will rise through the grate sections from directly below the same with the result that better combustion is obtained. In grates as heretofore constructed the air would pass directly through the forward grate sections of the stoker with the result that the grates further removed from the end of the stoker 95 would receive a less supply of air. It will 100 be obvious that my improvement overcomes these objections.
- What I claim is:
1. The combination of a plurality of grate sections arranged in longitudinal alinement, 105 one end of each section having a downwardly and forwardly extending extension adapted to underlie in spaced relation the end of the adjacent section, and a flange extending downwardly from said extension 110

and transversely thereof for cutting off flow of air between said sections.

2. The combination with grate supporting means, a plurality of grate sections arranged in longitudinal alinement, a downwardly and forwardly extending curved extension carried by one end of each of the grate sections and underlying the adjacent

end of the grate section next in order, and a downwardly directed flange carried by 10 each of the said extensions and extending the entire length thereof and engaging the grate supporting means.

In testimony whereof I affix my signature.

THOMAS J. COURTNEY.
